UNITED STATES PATENT OFFICE.

EDWARD THOMAS, OF NEW YORK, N. Y., ASSIGNOR, BY MESNE ASSIGNMENTS, TO
UNDERWOOD COMPUTING MACHINE COMPANY, OF NEW YORK, N. Y., A CORPO-
RATION OF NEW YORK.

COMBINED TYPE-WRITING AND COMPUTING MACHINE.

1,248,409.

Specification of Letters Patent.

Patented Nov. 27, 1917.

Application filed October 16, 1914. Serial No. 866,892.

To all whom it may concern:

Be it known that I, EDWARD THOMAS, a citizen of the United States, residing in New York city, in the county of New York and State of New York, have invented certain new and useful Improvements in Combined Type-Writing and Computing Machines, of which the following is a specification.

10 My invention relates to computing machines, and is herein disclosed as applied to a combined typewriting and computing machine of the Underwood-Hanson type, wherein the numeral keys of the typewriter 15 set up pins on denomination members or rack bars, and the numbers represented by the pins thus set up are later carried into computing wheels. Such typewriting machines are usually provided with a set of 20 tabulating keys for rapidly positioning the carriage at any desired column, and are also usually provided with denomination selectors or dogs which are settable along the typewriter carriage, and serve to determine 25 into what computing wheels the numerals written in any column shall be carried.

One object of my invention is to simplify the adjustments of the stop which is used to coöperate with the tabulating keys and the 30 denomination selector. For this purpose, I may provide that the denomination selector is pivoted in the usual manner to swing on a rod, but that the means for holding said selector in place along said rod shall be the tabulating stop itself. This enables a single 35 adjustment of the tabulating stop to determine not only in what column the typewriter carriage shall be arrested, but also practically compels the denomination selector to 40 be properly adjusted with reference thereto.

Other features and advantages will hereinafter appear.

In the accompanying drawing,

45 Figure 1 is a sectional side view of an Underwood-Hanson combined typewriting and computing machine, showing only so much thereof as seems advantageous to illustrate my invention.

Fig. 2 is a rear view of a denomination-selecting dog and some accompanying parts.

50 Fig. 3 is a side view of the same with a subtraction dog effective.

Fig. 4 is a perspective view thereof with a subtraction dog ineffective.

In the Underwood typewriting machine, 55 the usual numeral keys 1 and alphabet keys 2 depress the key levers 3 to cause bell cranks 4 to swing the type-bars 5 upwardly and rearwardly so that lower and upper case types 6 and 7 thereon print against a platen 60 8, which is carried in a traveling carriage 9. Said carriage is fed along at every operation of a numeral key, and for this purpose is provided with a rack 10 adapted to mesh with a pinion 11, said pinion being connected to the usual escapement wheel 12 on which the usual escapement dogs 13 and 14 are made effective through the usual universal bar 15 operated by the usual heels 16 on the type-bars 5. For positioning said 70 carriage rapidly at any point in the travel thereof, the machine is provided with decimal tabulating keys 17 on the front ends of key levers 18, the rear ends of said levers being adapted, when a key is depressed, to 75 raise the corresponding plunger 19 so that the upper end 20 thereof forming a counter-stop rises into the path of a column stop 21 mounted on the usual rack bar 22 of the Underwood typewriting machine. 80

Whenever one of the keys 17 is depressed it releases the typewriter carriage permitting said carriage to travel along until arrested by the striking of a column stop 21 against the upper end of a projected counter-stop 85 20. To accomplish this, each of the plungers 19 is provided with a heel 23, which is adapted to raise a small universal bar 24 pivoted on a shaft 25, so that the rock arm 26 on the forward end of said universal bar 90 will draw down a link 27 and thereby rock an arm 28, so as to cause a roll 29 on the forward end of said arm to lift the rack 10 out of mesh with the pinion 11, said rack for this purpose being pivoted on the carriage at 30.

As the typewriter carriage travels along, it raises into effective position one after another a series of denomination or computing members 31, so that the numeral key 100 operated at any moment may depress or set up on the computing member then in effective position the appropriate pin 32, each pin on any computing member 31 representing a digit. The means for doing this are 105 shown in the application of Hans Hanson, No. 626,550, filed May 11, 1911, and form no novel part of the present invention, but

include a pendant 33 on each numeral key, which pendant, as it descends, strikes a rock arm 34 so as to rock a shaft 35 to which said arm is fast, thereby operating its pin-setting linkage 36, causing the lower member 37 thereof to move downward and depress the pin on the effective rack bar corresponding to said linkage.

After a series of pins have thus been set 10 up on the various computation members, they are caused to rotate computing wheels 28, each to an extent dependent upon the key depressed. For this purpose, the computing wheels are provided with the usual 15 pinions 39, which mesh with racks 40 on the forward end of the computation bars 31, and said pinions are rotated by the forward movement of the computation bars. This forward movement is brought about by 20 means of a cross bar 41 forming part of a general operator, said cross bar being adapted to be moved forward and strike any depressed pins 32 in such a way as to carry the computation bars forward. The general 25 operator also comprises side bars 42, said bars including racks by which said operator is driven, the driving means being an idle pinion 43, which co-operates with the usual segment 44.

30 For raising the computation members 31 to effective position, the typewriter carriage is provided with one or more dogs 45, which are adjustable thereon, and when in effective position ride under and raise one after another 35 a series of jacks 46, there being one jack for each computing wheel 38, and correspondingly one for each computation member 31. When a dog 45 stands under any jack 46, said jack depresses a rod 47 at 40 the rear end thereof, so as to rock downwardly the rear end of a lever 48, causing the front end 49 thereof to lift the appropriate computation member 31, thereby bringing the pins thereon within the range 45 of the pin-setting linkages 36.

Since the typewriter carriage travels from the right toward the left, while numbers have to be inserted in the computing wheels, beginning at the left and then *seriatim* toward the right, a transposing device 50 is provided for causing the carriage in its letter-feeding movement to raise the computation members one after another to effective position, beginning with the left-hand one. 55 The dogs 45 are usually cams pivoted at 51, so as to be effective on the jacks 46 in one direction only as they travel past them. The pivots 51 are formed in blocks 52 which are pivoted on the usual rod 53 on the carriage of the typewriter, said rod comprising 60 grooves 54 and 55 which co-operate with a spring ball detent 54^a in the block 52 to hold the block approximately in either effective position (see Fig. 1) or swung up to 65 ineffective position, as shown in dotted lines

in Fig. 3. The detent 54^a is not sufficient to locate the blocks 52 so as to hold the cams 45 thereon in effective position; but in the adding zone, the blocks 52 are supported on a roll 56, said roll being mounted on 70 swinging arms 57, so that it may be swung outwardly, as seen in Fig. 3, to silencing position, or inwardly, as shown in Fig. 1, at effective position. When in effective position, the silencing roll 56 supports a block 75 52, which is in the adding zone, by a cam roll 58 thereon, thereby lifting said block to carry its cam 45 to effective position.

The silencing roll 56 is tapered at its ends, and is of the type shown in the application 80 of John N. Thornton, Serial Number 690,488, filed April 13, 1912, being held normally in effective position by a spring 59.

In order to hold any block 52 against sliding on the rod 53, the blocks are provided with means for co-operating with the usual column stops 21. For this purpose each block 52 is provided with a large slotted lug at the bottom thereof, which is T-shaped, having the slot 60 running into 90 the stem of the T, and a wing 61 extending at each side thereof. Said slot is made approximately the thickness of a column stop, and the lug extends down far enough so that said slot will normally engage one of 95 the column stops unless the block is thrown upward to the dotted line position shown in Fig. 3. When a block 52 thus engages a column stop, it is held against sliding, and the slot 60 is of such a height that sufficient 100 freedom of vertical movement is given to the blocks to permit them to be dropped down to ineffective position, as seen in Fig. 3, but the slot is cut off at such a height that it is impossible for the block to drop 105 far enough to interfere with any other mechanism.

While the wings 61 on the block are not necessary, they are convenient in setting the block, because they enable the operative to 110 approximately locate the block with one of said wings resting on a column stop, and then sliding the block along until it drops into place onto a column stop. To facilitate this, the slot may be made slightly V-shaped 115 at the point where it would naturally first engage said stop, although it preferably fits said stop fairly closely at other points, to avoid lost motion. These wings 61 may be of any desired width, but where cross adding is likely to be done, said wings are preferably not long enough to interfere with two columns of numbers being computed as close to each other as the column stops would ordinarily be set, namely, ten letter-spaces 120 apart. The wings 61 are advantageously long enough to prevent two selectors being set so close together as to permit of the typist's attempting to compute two sets of numbers on the same computing wheels only 125 130

a few wheels apart. The disadvantage of computing two sets of numbers so close together is that one set of numbers is likely to add up to a sufficiently large number to 5 overlap into the number in the next column, with the result that the computation is inextricably confused.

Further, if two column stops are set so close together that there are fewer letter-spaces between them than there are decimal stops 20, the carriage may be stopped at an incorrect position under some circumstances. This is so because if a certain column stop is 15 designed to arrest the carriage at a given column when the units decimal key is depressed, any column stop located nearer than the most remote decimal stop would manifestly be within range also of the decimal stops, the result being that some decimal stops 20 will coöperate with one column stop, and some decimal stops will coöperate with another column stop in arresting the carriage, so the typist will be at sea as to what is going to happen in using the tabulating device. Where such wings as I have 25 provided, are associated with the column stops, it is impossible to make mistakes of this character.

The denomination-selecting cam or tappet 45 which is in the adding zone, may be automatically dropped to ineffective position when a tabulating key is depressed. For this purpose the universal bar 24, through its shaft 25, operates a rock arm 35 63 having a pin-and-slot connection with a link 64. Said link, whenever the universal bar 24 is lifted by a tabulating key, swings the shaft 65 on which the silencing roll 56 is supported rearwardly, with the result 40 that the block 52 drops down to ineffective position clear of the dogs 45.

The machine may also include a platen shift key adapted to determine whether the lower case types 6 or the upper case types 45, 7 shall be effective to print on the platen. Said key is of the usual type, and operates at its rearward end a bell-crank 67 by means of an upstanding arm 68 to lift said platen by means of the usual rail 69 on which the 50 wheel 70 runs. Whenever the platen shift key is depressed to raise the rail 69, a silencing arm 71 fast to said bell-crank 67, and extending to the rear thereof, is rocked downwardly, and thereby causes a follower 55 72 thereon to cam the roll 56 to ineffective position, by means of a cam 73 on an arm fast to the shaft 65.

The mechanism may also include subtraction means, such as are shown in the 60 application of Ogden Minton, Serial Number 797,714, filed October 28, 1913, which is of the complementary type, the connections being such that when subtraction is being done, each key operated, instead of depressing the key it does in addition, de-

presses a key representing the complement of the number set up in addition.

Certain other connections are made effective whenever the subtraction means becomes effective, but the details of the subtraction device are shown in the application of Ogden Minton, above referred to, and it is not believed to be necessary to recite them herein. The subtraction is made effective by a bar 75 which is normally held 70 in its ineffective or addition position by a dog 76. Whenever the dog 76 is released in the manner to be described later, the release of this dog permits the spring 77 to draw the subtraction bar 78 rearwardly, causing 80 said bar to be effective on all the "9" pins 32 to set them to effective position, and at the same time shifts the rock shafts 35 so that they operate pin-setting bars 36 complementary to those they previously operated. 85

The dog 76 is moved to its ineffective position by a spring 79 but is normally held in effective position by connections not material to the present invention, it being sufficient to say that said connections are under 90 the control of a vertical rod 80, which is controlled by a dog 81 adjacent the casing 82 of the decimal stop frame, said dog being adapted to be struck by specially formed 95 column stops 21.

The connections are provided so that a column stop 21 may pass the dog 81 idly on the return movement of the carriage, but on the forward movement of the carriage 100 an extension 83 on the column stop is effective to operate the dog 76 through the vertical rod 80. The extensions 83 of the column stops to be thus effective, as shown most clearly in Fig. 3, are triangular extensions of said stops so that said stops on one side are of the normal length, but on the opposite side are extended as at 83. This construction enables a single set of column stops to be used in either addition or subtraction, because any column stop with its extension 83 uppermost will be effective as an ordinary mere adding column stop, while with said extension downward it becomes effective as a subtraction-setting dog. The 115 result is that any column stop may be set to addition or subtraction, and no matter which position it is setting it serves to accurately locate the tappet 45 at the exact letter-space required. 120

Variations may be resorted to within the scope of the invention, and portions of the improvements may be used without others.

Having thus described my invention, I claim:

1. In a combined typewriting and computing machine, the combination with numeral keys and a traveling carriage, of computing wheels, a column stop settable on said carriage, tabulating keys for position- 130

ing said carriage by said stop, a denomination selector settable on said carriage, means forming part of said selector and coöperating with said stop to hold said selector against sliding, means whereby said denomination selector may be set at an ineffective position in which it is disconnected from said stop, means whereby said selector is normally in a second ineffective position in which it remains connected with said stop, a device adapted to restore said selector from its second ineffective position to effective position when it reaches the adding zone, and means adapted to hold said device in its second ineffective position while passing through said adding zone whenever a tabulating key is depressed.

2. In a combined typewriting and computing machine, the combination with numeral keys and a traveling carriage, of computing wheels, a column stop settable on said carriage, a denomination selector comprising a block settable along said carriage, two walls on said block to coöperate with said column stop and hold said selector against sliding, and extensions from said walls adapted to coöperate with said column stop to support said selector in an unusual position when inaccurately located with reference to said column stop.

3. In a combined typewriting and computing machine, the combination with numeral keys and a traveling carriage, of separately settable denomination selectors on said carriage, a gang of computing wheels, and means for preventing said selectors from being located closer together than the number of wheels in a gang.

4. In a combined typewriting and computing machine, the combination with numeral keys and a traveling carriage, of column stops for positioning said carriage, a series of denominational counter-stops, separately settable denomination selectors adapted to be held in position by said stops, and means for preventing two selectors from being set closer together than the number of letter-spaces covered by said denominational counter-stops.

5. In a combined typewriting and computing machine, the combination with a traveling carriage and a denomination selector, of an array of denomination stops for positioning said carriage, a column stop for positioning said selector, and wings associated with said selector extending the width of

said denomination stops, for preventing the location of any other selector similarly provided nearer than the width of said array of denomination stops.

6. In a combined typewriting and computing machine, the combination with computing mechanism, of typewriting mechanism coöperating with said computing mechanism, to effect a combined typewriting and computing action, and including a traveling carriage, a denominational selector for said computing mechanism, adjustably mounted on said carriage, and a separately settable column stop for determining a typewriting zone engageable by said denominational selector to determine mechanically the location of the selector on said carriage, for a computing zone corresponding with the typewriting zone determined by said stop.

7. The combination with a letter-feeding carriage and a denomination selector, of a column stop for said carriage independently settable, but adapted to positively hold said selector at the corresponding letter-space of the carriage.

8. In a computing machine, the combination with a letter-feeding carriage, of a denomination selector including a block slideable on said carriage, a column stop independently settable to select a column for said carriage, and an extension of said block adapted to slidably engage said stop to permit said selector to be swung relatively thereto into and out of effective position on said carriage, and in both positions adapted to positively hold said selector against sliding along the carriage.

9. In a computing machine, the combination with a letter-feeding carriage, of a denomination selector including a block slideable on said carriage, a column stop independently settable to select a column for said carriage, and an extension of said block adapted to slidably engage said stop to permit said selector to be swung relatively thereto into and out of effective position on said carriage, and in both positions adapted to positively hold said selector against sliding along the carriage, said selector also shiftable to a third position in which it is ineffective, and in which it may be slid along the carriage independently of the stop.

EDWARD THOMAS.
